(57) **CLAIM**

The ornamental design for an electric drifter axle, as shown and described.

DESCRIPTION

FIG. 1 is a top perspective view of an electric drifter axle, showing our new design;

FIG. 2 is a right side view of FIG. 1;

FIG. 3 is a left side view of FIG. 1;

FIG. 4 is a front view of FIG. 1;

FIG. 5 is a rear view of FIG. 1;

FIG. 6 is a top view of FIG. 1; and,

FIG. 7 is a bottom view of FIG. 1.

The broken lines shown illustrate portions of the electric drifter axle that form no part of the claimed design.
